[57] CLAIM

The ornamental design for set of end units for balustrades, as shown and described.

DESCRIPTION

FIG. 1 is a perspective view of a set of end units for balustrades, showing my new design;

FIG. 2 is a fragmentary side elevational view of the upper end thereof;

FIG. 3 is a fragmentary side elevational view of the lower end thereof;

FIG. 4 is an elevational view thereof as seen from the upper end;

FIG. 5 is an elevational view thereof as seen from the lower end; (the broken lines showing the escalator stairs are for illustrative purposes only and form no part of the claimed design);

FIG. 6 is a ground plan view of the upper and lower end thereof;

The broken lines showing the escalator stairs, the middle portion of the balustrade and the mechanical housing are for illustrative purposes only and form no part of the claimed design.

The views of FIGS. 4-6 are shown broken away for ease of illustration.
